(57) **CLAIM**

I claim the ornamental design for the spinal fusion cage, as shown and described.

DESCRIPTION

FIG. 1 is a top, rear perspective view of a spinal fusion cage according to an embodiment of the disclosure.

FIG. 2 is a bottom, front perspective view of the spinal fusion cage of FIG. 1.

FIG. 3 is a top view of the spinal fusion cage of FIG. 1. The bottom view of the spinal fusion cage of FIG. 1 is identical. FIG. 4 is a left side view of the spinal fusion cage of FIG. 1.

FIG. 5 is a right side view of the spinal fusion cage of FIG. 1.

FIG. 6 is a front view of the spinal fusion cage of FIG. 1. FIG. 7 is a rear view of the spinal fusion cage of FIG. 1. FIG. 8 is a top, rear perspective view of a spinal fusion cage according to an embodiment of the disclosure.

FIG. 9 is a bottom, front perspective view of the spinal fusion cage of FIG. 8.

FIG. 10 is a top view of the spinal fusion cage of FIG. 8. The bottom view of the spinal fusion cage of FIG. 8 is identical. FIG. 11 is a left side view of the spinal fusion cage of FIG. 8.

FIG. 12 is a right side view of the spinal fusion cage of FIG. 8.

FIG. 13 is a front view of the spinal fusion cage of FIG. 8; and,

FIG. 14 is a rear view of the spinal fusion cage of FIG. 8. The portions shown in dashed lines form no part of the claimed design.
